CLAIM

The ornamental design of a power nozzle for a vacuum cleaner, as shown and described.

DESCRIPTION

FIG. 1 is a perspective view of a power nozzle for a vacuum cleaner showing our new design;

FIG. 2 is a left side elevational view thereof;

FIG. 3 is a right elevational view thereof;

FIG. 4 is a top plan view thereof;

FIG. 5 is a front elevational view thereof;

FIG. 6 is a rear elevational view thereof; and,

FIG. 7 is a bottom view thereof.

The portion of the power nozzle shown in broken lines is for illustrative purposes only and forms no part of the claimed design.
